ELECTRODYNAMOMETER

Filed July 20, 1946

UNITED STATES PATENT OFFICE

2,508,379

ELECTRODYNAMOMETER

Cecil L. Freedman, Pittsburgh, Pa., assignor to
Westinghouse Electric Corporation, East Pitts-
burgh, Pa., a corporation of Pennsylvania

Application July 20, 1946; Serial No. 685,056

11 Claims. (Cl. 171—95)

1 This invention relates to electrical instruments, and it has particular relation to electrical measuring instruments of the electrodynamic type.

In the electrical industry, it is frequently necessary or desirable that instruments be provided which are responsive to quantities in polyphase and three-wire alternating-current circuits and to quantities in three-wire direct-current circuits. Such instruments may take the form of two-element electrodynamic instruments having two complete elements with both of the moving coils of the elements mounted on a common shaft. Conventional prior art two-element electrodynamic instruments generally employed no iron cores because of constructional difficulties and because of errors introduced by the utilization of iron for the cores. A discussion of electrodynamic or dynamometer instruments will be found in volume 1 of Electrical Measuring Instruments by Drysdale and Jolley published in 1924 by D. Van Nostrand Company, New York city. The discussion is presented in chapter VIII and two-element or "double" wattmeters are treated in a section beginning on page 341.

In the Lunas application, Serial No. 570,028, filed December 27, 1944, a two-element electrodynamic instrument is disclosed which has iron cores. These iron cores are so constructed that the rotor assembly of the instrument can be removed from the stator assembly without disturbing the iron cores in any way. Furthermore, Lunas discloses the provision of reversely associated iron cores which produce opposed solenoid forces acting on the moving coil assembly. Consequently, errors resulting from solenoid action are reduced or substantially eliminated. Reference also may be made to the application of D. A. Young et al., Serial No. 500,896, filed September 2, 1943, now Patent No. 2,438,027, issued March 16, 1948. Both of the aforesaid applications and the present application are assigned to the same assignee.

In accordance with the invention, a compact coplanar electrodynamic instrument is provided which is suitable for replacing prior art two-element electrodynamic instruments. The invention contemplates the provision of a moving coil assembly wherein two coil sides are angularly displaced about a common portion of a common shaft. Each of the coil sides has an independent magnetic field provided by an independent magnetic path defining an air gap for the associated coil side. The magnetic paths are so configured that the moving coil or rotor assembly may be removed from the associated stator assembly without disturbing the magnetic structure in any way. Solenoid action is reduced or substantially eliminated by dividing the magnetic structure into sections which apply opposed solenoid forces to the rotor assembly.

It is, therefore, an object of the invention to

2 provide an improved electrodynamic electrical instrument suitable for replacing prior art two-element electrodynamic instruments.

It is another object of the invention to provide an electrodynamic instrument having a moving coil assembly wherein two coil sides are angularly displaced about a common portion of an axis for energization, respectively, by independent magnetic fields.

It is an additional object of the invention to provide an electrodynamic instrument having a single coil mounted for rotation about an axis intermediate two sides of the coil and provided with an independent magnetic field for each side of the coil.

It is a further object of the invention to provide an electrodynamic instrument having a moving coil assembly wherein two coil sides are angularly displaced about a common portion of an axis, wherein a separate magnetic field is provided for each of the coil sides, and wherein a magnetic structure is provided which is configured to permit removal of the coil assembly therefrom without disturbing the magnetic structure.

It is also an object of the invention to provide an electrodynamic instrument having a moving coil assembly providing two coil sides disposed angularly about a common portion of an axis and having a separate magnetic field for each of the coil sides, with a magnetic structure configured to substantially eliminate solenoid action between the magnetic structure and the moving coil assembly.

Other objects of the invention will be apparent from the following description taken in conjunction with the accompanying drawing, in which:

Figure 1 is an exploded view in perspective of an electrodynamic instrument embodying the invention;

Fig. 2 is a view in perspective, with parts broken away, of an electrodynamic instrument embodying a modified form of the invention;

Fig. 3 is a schematic view illustrating suitable connections for the electrical instrument of Fig. 1;

Fig. 4 is a plan view, with portions broken away, of an electrodynamic instrument illustrating a further modification of the invention; and

Fig. 5 is a view in plan of an electrical instrument representing a further modification of the invention.

Referring to the drawing, Fig. 1 shows an electrodynamic instrument having a stator assembly 1 and a rotor assembly 3. The rotor assembly includes a shaft 5, which is mounted for rotation relative to the stator assembly by means of suitable bearing screws 7 and 9 which are secured to the stator assembly. The shaft 5 has attached thereto a moving coil assembly which comprises a coil 11. This coil has terminals connected, respectively, to the inner ends of two flexible, spiral,

conductive strips 13 and 15. The inner ends of the spiral conductive strips 13 and 15 are secured to insulating bushings 17, which are attached to the shaft 5. The outer ends of the conductive strips 13 and 15 are soldered or otherwise secured to terminal lugs 19 and 21, which are secured to the stator assembly but which are insulated therefrom.

In order to damp rotation of the rotor assembly, an electroconductive disk 23 is secured to the shaft 5. This disk rotates between the poles of a permanent magnet 25 to damp rotation of the rotor assembly in a manner well understood in the art.

The rotor assembly is biased in a predetermined direction by means of a control spring 27 having its inner end attached to the shaft 5 and having its outer end secured to a lever 29 which is pivotal about the bearing screw 7. Pivotal movement of the lever 29 is employed for adjusting the zero position of the rotor assembly in a manner well understood in the art.

Rotation of the rotor assembly 5 may be employed in various ways, as, for example, to actuate electrical contacts for relaying purposes and for actuating pointers associated with a scale for indicating the extent of movement of the rotor assembly relative to the stator assembly. For the purpose of illustration, a recording pen 31 is attached to the shaft 5 for rotation therewith. This pen moves across the face of a chart 33 to leave a record of the movement of the rotor assembly on the chart. The chart 33 may be advanced continuously or intermittently in a manner well understood in the art for providing a record of quantities measured by the rotation of the rotor assembly.

In order to develop torques between the rotor and stator assemblies, magnetic fields are provided for two coil sides 11a and 11b of the coil 11. These magnetic fields may be developed in response to currents flowing, respectively, in fixed windings 35 and 37. When current flows in the coil 11, the reactions between such current and the two magnetic fields associated with the coil sides 11a and 11b result in the application of torques to the shaft 5 which are dependent on the magnitude of the current in the coil 11 and the magnitudes of the currents in the fixed windings 35 and 37.

In order to provide a compact and efficient electrodynamic instrument, a magnetic structure is provided which includes a magnetic section 39. This magnetic section comprises a magnetic core 41, which has a passage 43 therethrough dividing the magnetic core into two inner pole pieces 45 and 47. The inner pole piece 45 is spaced from an outer pole piece 49 to provide an air gap 51 within which the coil side 11a is positioned for rotation. The outer pole piece 49 has a neck passing through the fixed winding 35 and is connected to the inner pole piece 45 by means of a magnetic connector 53. It will be noted that the outer pole piece 49, the air gap 51, the inner pole piece 45 and the magnetic connector 53 define a magnetic path for magnetic flux produced by current flowing in the winding 35. This magnetic path is represented in Fig. 1 by a dotted line 55.

In a somewhat similar manner, an outer pole piece 57 is spaced from the inner pole piece 47 to define an air gap 59 within which the side 11b of the coil 11 is positioned for rotation. The outer pole piece 57 has a neck passing through the fixed winding 37 and is connected to the inner pole piece 47 by means of a magnetic connector

61. Consequently, the outer pole piece 57, the magnetic connector 61, the inner pole piece 47 and the air gap 59 define a path for magnetic flux produced by current flowing in the fixed winding 37, which is indicated by a dotted line 63.

6 In order to permit the utilization of short air gaps and to permit accurate centering of the coil 11, it is desirable that the inner and outer pole pieces be permanently and rigidly associated with each other. Such association is accomplished in 10 the embodiment of Fig. 1 by means of a connecting element 65 extending between the outer pole piece 49 and the inner pole piece 47. Conveniently, the entire magnetic section 39 may be 15 constructed from a plurality of similar unitary laminations of soft magnetic material which are united to each other by means of suitable rivets 67. Each lamination is accurately punched from 20 a sheet of magnetic material to provide portions of the pole pieces 45, 47, 49 and 57, the connectors 53 and 61 and the element 65.

It will be noted that the magnetic paths 55 and 63 are substantially magnetically independent of each other. The magnetic paths represented by 25 the dotted lines 55 and 63 are united by a connecting element 65 which for convenience is made of magnetic material. However, by inspection of Fig. 1, it will be noted that magnetic fluxes produced by currents flowing in the windings 35 and 30 37 flow in separate magnetic paths provided by the magnetic section 39. Consequently, the magnetic fields produced in the air gaps 51 and 59 in response to independent energizations of the fixed 35 windings 35 and 37 are substantially magnetically independent of each other. For this reason, the coil 11 and the windings 35 and 37 may be energized, respectively, by three separate quantities. Suitable connections for such a purpose will be discussed below.

40 The configuration of the magnetic section 39 is such that the coil 11 may be removed from operative position relative to the magnetic section and returned to operative position without disturbing the magnetic section in any way. In order 45 to remove the coil 11 from the magnetic section 39, the permanent magnet 25 and the bearing screw 7, together with its support, may be removed and the strips 13 and 15 may be disconnected from the lugs 19 and 21. The rotor assembly 50 is then rotated in a clockwise direction, as viewed from the control-spring end of the shaft 5, to its extreme position wherein the coil 11 is aligned with the passage 43. The rotor assembly 55 may then be moved in a direction parallel to the shaft 5, free of the magnetic section 39. A reverse procedure may be followed for reinserting the coil in operative position relative to the magnetic section 39.

Although the structure of Fig. 1 thus far specifically described may be employed for measuring purposes, some error may be introduced by solenoid action. Such action may be understood by considering the effect of current passing through the coil 11 when the fixed windings 35 and 37 are deenergized. It will be noted that the paths 55 and 63 are asymmetric with respect to the paths of rotation of the coil sides 11a and 11b. When current passes through the coil 11, the coil seeks a position such that the magnetic reluctance offered to magnetic flux produced by current flowing in the coil 11 is a minimum. For the instrument of Fig. 1, solenoid action produced by the magnetic section 39 tends to urge 70 the rotor assembly in a counterclockwise direc-

tion, as viewed from the control spring end of the shaft 5.

In order to reduce or eliminate errors introduced by solenoid action, the magnetic structure of Fig. 1 includes a second magnetic section 69 which is exactly similar in construction to the magnetic section 39, and parts thereof are identified by similar reference characters. However, it will be noted that the magnetic section 69 is reversed relative to the magnetic section 39 about an axis transverse to the shaft 5. This means that the solenoid forces applied by the two magnetic sections to the coil 11 are oppositely directed, and the resultant solenoid force is substantially reduced or eliminated. This construction for reducing or eliminating solenoid action is disclosed in the aforesaid Lunas application.

The magnetic sections 39 and 69 are spaced apart for certain purposes. Such spacing prevents the short-circuiting of portions of the magnetic sections which are at different magnetic potentials. In addition, the sections are spaced apart by a distance sufficient to permit rotation of an end 11c of the coil 11 therebetween. This facilitates removal of the coil 11 from operative position relative to the magnetic structure and the return of the coil 11 to operative position without disturbing the magnetic structure.

To understand the procedure for removing the coil 11, let it be assumed that it is desired to remove the coil 11 from operative position. The coil 11 first is rotated to its extreme position in a clockwise direction, as viewed from the control-spring end of the shaft. This brings the coil 11 into alignment with the passage 43 of the magnetic section 39. It will be noted that the connector 65 is located outside the passage 43 and outside the path of the coil, and does not interfere with the desired removal of the coil. With the coil in alignment with the passage 43, the rotor assembly may be moved in a direction parallel to the shaft 5 until the end 11c of the coil engages the magnetic section 69. It will be understood that the permanent magnet 25 and the bearing screw 7 and its support first should be removed, and the strips 13 and 15 should be disconnected from the lugs 19 and 21 prior to such axial movement of the rotor assembly.

With the end 11c of the coil intermediate the two magnetic sections 39 and 69, the rotor assembly is rotated to its extreme position in a counterclockwise direction, as viewed from the control spring end of the shaft, to bring the coil assembly into alignment with the passage 43 of the magnetic section 69. The rotor assembly then may be moved in a direction parallel to the shaft 5 to remove the coil 11 completely from the magnetic section 69 and the associated magnetic structure. A reverse sequence may be followed for returning the coil 11 to its operative position. It will be noted that during such removal and return of the coil, the associated magnetic structure is not disturbed. This is desirable for the reason that any disturbance of the magnetic structure may result in a change in the calibration of the instrument.

Conveniently the magnetic sections 39 and 69 may be spaced by means of spacers 71 and 73. If of magnetic material, the spacers should be so configured that they do not short portions of the magnetic sections which are intended to operate at different magnetic potentials. If desired, however, the spacers may be made of non-magnetic material. Preferably, the spacers are located

only at the ends of the magnetic sections in order to facilitate inspection of the clearance between the pole pieces of the magnetic section 39 and the pole pieces of the magnetic section 69. The magnetic structure of Fig. 1 is shown in assembled condition in Fig. 2. The magnetic sections, together with the associated spacers, may be secured to each other by means of suitable rivets 75.

It will be noted that the inner pole pieces are of tapered configuration. For instance, the pole piece 45 tapers from a predetermined cross section adjacent the magnetic connector 53 to a smaller cross section adjacent the opposite end of the inner pole piece 45. Inasmuch as the magnetic flux decreases with the decrease in cross section, such configuration maintains a substantially uniform flux density in the inner pole piece and provides a large passage 43.

Circuit connections suitable for the instrument of Fig. 1 are illustrated in Fig. 3. In Fig. 3 a three-wire circuit having conductors L1, L2 and L3 are shown. These may be the conductors of a single-phase, three-wire circuit or the conductors of a three-wire, direct-current circuit. In the majority of such circuits, voltage unbalance between the outer conductors and neutral are not unduly large.

It will be noted that the winding 35 of the instrument is disposed for energization in accordance with current flowing through the outer conductor L3. The winding 37 of the instrument is disposed for energization in accordance with current flowing in the outer conductor L1. The coil 11 is connected for energization through a suitable impedance, such as a resistor 77, in accordance with the voltage between the outer conductors L1 and L3. No connection is made to the neutral conductor L2. With the connections illustrated in Fig. 3, the instrument would measure the power flowing in the three-wire circuit.

The modification illustrated in Fig. 2 is exactly similar to that of Fig. 1 except for the construction of the moving coil assembly. In Fig. 2 the moving coil assembly includes two independent coils 79 and 81. These coils are spaced angularly about a common portion of the shaft 5 to position one side of the coil 79 in the air gap 51 and one side of the coil 81 in the air gap 53. Since these coils are substantially equidistant from a plane transverse to the axis of the rotation thereof, the instrument of Fig. 2 may be termed a coplanar instrument. The coil 79 may have its terminals connected to spiral conductor strips similar to the strips 13 and 15 of Fig. 1. In a similar manner, the coil 81 may have its terminal connected to two additional conductor strips (not shown). This construction permits independent energization of the two coils 79, 81. Consequently, the instrument of Fig. 2 is the equivalent of a prior art two-element electrodynamic instrument and may be employed similarly. One element would include the coil 79 and the fixed winding 35, whereas the second element would include the coil 81 and the fixed winding 37.

It will be noted that one side of each of the coils 79 and 81 is adjacent the shaft 5. This means that some coupling may exist between the two coils. Such coupling would not be objectionable for the application of the instrument to Fig. 2 to direct-current circuits or for many applications of the instrument to measurement of quantities in alternating-current circuits. However, this coupling may be minimized by suitable

spacing of the coils from each other or suitable shielding as desired. The coil assembly of Fig. 2 may be removed from operative position with respect to the associated magnetic structure and returned to operative position in the same manner discussed with reference to the coil 11 of Fig. 1.

The instrument of Fig. 4 is similar to the instrument of Fig. 1, except for the configuration of the air gaps associated with the coil assembly 83, and the omission of the control spring 27 of Fig. 1. This coil assembly 83 may be similar to the coil 11 of Fig. 1 or the coil assembly of Fig. 2. However, for the purpose of discussion it will be assumed that the coil assembly 83 corresponds to that of Fig. 1. It will be noted that the instrument of Fig. 4 provides an air gap 51a which increases from a predetermined length A to a longer length B. In a similar manner the air gap 59a increases from a length C, which may be equal if desired to the length A, to a longer length D, which may be equal to the length B.

Let it be assumed that the coil assembly 83 is energized in accordance with a predetermined quantity and that the winding 35 is energized to produce a torque urging the rotor assembly in the direction of the arrow E. Let it be assumed further that the winding 37 is energized to urge the rotor assembly in the direction of the arrow F. The rotor assembly then will seek a position wherein the torques applied thereto in response to current flowing through the windings 35 and 37 are equal. If such a condition is illustrated in Fig. 4 and if the current through the winding 35 should decrease for any reason, the rotor assembly would rotate in the direction of the arrow F. Such rotation carries the coil side disposed in the air gap 51a into a stronger portion of the magnetic field. At the same time the movement of the rotor assembly carries the coil side disposed in the air gap 59a into a weaker field. The rotation of the coil continues until the torques are again balanced. Consequently, the instrument of Fig. 4 may be considered a ratio-type instrument. Applications for instruments of this type are known in the art.

As pointed out in my copending application, Serial No. 683,057, filed July 20, 1946, the construction of a magnetic structure to permit the insertion of a coil assembly therethrough into operative position and to permit removal of the coil assembly from operative position without disturbing the magnetic structure permits the utilization of complex magnetic structures. For example, in Fig. 5 a magnetic structure is disclosed wherein four air gaps are provided for two separate coils of a coil assembly 100. These coils 79a and 81a correspond to the coils 79 and 81 of Figure 2 except for the additional radial spacing of the coils from the associated shaft 5. Such spacing renders negligible the previously mentioned coupling between the two coils.

For providing magnetic fields within which the coils 79a and 81a are disposed for operation, a magnetic structure 101 is provided which includes two magnetic cores 103 and 105. The coil 79a surrounds the magnetic core 103 whereas the coil 81a surrounds the magnetic core 105. The magnetic cores are concentric about the shaft 5 and form, in effect, a resultant annular magnetic core having a diametric passage 107 extending therethrough. The passage is proportioned to permit movement of the coil assembly 100 therethrough in a direction parallel to the shaft 5.

The magnetic core 103 has a first magnetic pole piece 109 spaced from the outer surface of the core to define an air gap 111 therebetween. One side of the coil 79a is disposed for rotation through this air gap. A second magnetic pole piece 113 is spaced from the inner surface of the magnetic core 103 to define an air gap 115 within which a second side of the coil 79a is disposed for rotation. In a similar manner, the magnetic core 105 is provided with a first magnetic pole piece 117 and a second magnetic pole piece 119 to define air gaps 121 and 123 for reception of two sides of the coil 81a.

The magnetic structure 101 includes a magnetic ring 125 which substantially surrounds the pole pieces and magnetic cores and which is magnetically connected to each of the pole pieces and magnetic cores. For example, the magnetic cores 103 and 105 are connected to the magnetic ring by means of magnetic connectors 127 and 129. The pole pieces 113 and 119 are connected to the magnetic ring through magnetic connectors 131 and 133. It will be noted that all portions of the magnetic structure are clear of the passage 107 and do not interfere with removal of the coil assembly through the passage in a direction parallel to the shaft 5 through the passage. Each of the four air gaps 111, 115, 121 and 123 communicates with the passage 107 to permit rotation of the coil 79a and 81a in a counterclockwise direction as viewed in Fig. 5 into the passage 107 for removal therethrough.

In order to establish magnetic fields in the air gaps, the fixed windings 35 and 37 surround respectively the magnetic connectors 129 and 127. As examples of suitable polarities, the windings 35 and 37 when energized may produce north poles N and south poles S as indicated in Figure 5. If the windings are energized by alternating currents, the indicated polarities are instantaneous polarities.

In order to segregate further the magnetic circuits associated with the windings 35 and 37, the magnetic ring 125 may be provided with an opening 137. Since the magnetic circuits are independent, the coil 79a and the winding 37 may be energized independently of the winding 35 and the coil 81a to provide a two-element electrodynamic instrument.

The magnetic structure 101 may be formed of similar magnetic laminations secured to each other by means of rivets 139. Each lamination may be punched accurately from a sheet of magnetically soft iron or steel.

If it is desired to compensate the instrument of Figure 5 for errors introduced by solenoid action, the magnetic structure may be divided into two sections; each similar to the section or magnetic structure 101 illustrated in full lines in Figure 5, but reversed with respect to each other about the line A—A. The two sections 101 and 101a are associated with the same coils 79a and 81a and with the same fixed windings 35 and 37 in the manner discussed with reference to Figure 2. In order to avoid confusion, the added section 101a is shown in broken lines in Fig. 5.

In operation the instrument of Figure 5 may be connected in conformance with the connections employed for any conventional prior art two-element electrodynamic instrument. For example, if the instrument is associated with a two-phase alternating current circuit, the coil 79a may be energized in accordance with the voltage across a first phase while the fixed winding 37 is adjusted in accordance with the current flow-

ing in the first phase. The coil 81a may be energized in accordance with the voltage of the second phase of the circuit, whereas the fixed winding 35 is energized in accordance with the current flowing in the second phase. When so connected the instrument measures power supplied through the two-phase circuit.

Although the invention has been described with reference to certain specific embodiments thereof, numerous modifications are possible. Therefore, the appended claims have been drafted to cover not only the specific embodiments herein illustrated, but also all modifications embodying the invention.

I claim as my invention:

1. In an electrical instrument responsive to a function of three variable quantities, a stator assembly, a rotor assembly comprising a coil, and means mounting the coil for rotation relative to the stator assembly about an axis, means for energizing the coil in accordance with a first variable quantity, said stator assembly comprising field means responsive to a second variable quantity for establishing a first magnetic field for a first portion of the coil, and second field means magnetically independent of said first-named field means and responsive to a third variable quantity for establishing a second magnetic field for a second portion of the coil, whereby rotation of the coil is a function of said three quantities.

2. In an electrical instrument responsive to a function of three variable quantities, a stator assembly, a rotor assembly comprising a coil, means mounting the coil for rotation relative to the stator assembly about an axis, means for energizing the coil in accordance with a first variable quantity, field means responsive to a second variable quantity for establishing a first magnetic field for a first portion of the coil, and field means magnetically independent of said first-named field means and responsive to a third variable quantity for establishing a second magnetic field for a second portion of the coil, whereby rotation of the coil is a function of said three quantities, said stator assembly having a passage therein through which the coil is removable from operative position without disturbing the means for establishing said magnetic fields.

3. In an electrical instrument, a stator assembly, a rotor assembly comprising coil means, means mounting the coil means for rotation relative to the stator assembly about an axis, said stator assembly comprising a unitary magnetic member having two magnetically-independent magnetic paths each including an arcuate air gap positioned to receive a coil side of the coil means, said magnetic member having a passage through which the coil means may be removed from operative position without disturbing said magnetic paths.

4. In an electrical instrument, a stator assembly, a rotor assembly comprising coil means, means mounting the coil means for rotation relative to the stator assembly about an axis intermediate two of the coil sides, said sides being equidistant from any point on the axis, said stator assembly comprising a first unitary magnetic member having two magnetically-independent magnetic paths each including an arcuate air gap positioned to receive a separate one of said coil sides of the coil means, and a second magnetic member having two magnetically-independent magnetic paths each including an arcuate air gap positioned to receive a separate one of said coil sides, said magnetic paths being asymmetric with

respect to the paths of travel of said coil sides to produce solenoid forces acting on the coil means, the asymmetries of the magnetic paths associated with each of said coil sides being oppositely directed for substantially cancelling said solenoid forces, and separate means for directing magnetic flux through the magnetic paths associated with each of said coil sides.

5. In an electrical instrument; coil means; a magnetic structure including two separate inner pole pieces and two separate outer pole pieces, said pole pieces being arranged in pairs wherein each pair comprises an inner pole piece and an outer pole piece spaced to define an air gap for a separate one of two sides of said coil means, and magnetically-independent means for directing magnetic flux through each of said air gaps; and means mounting said coil means for rotation relative to said magnetic structure about an axis intermediate said two sides of the coil means, said inner pole pieces being spaced to define a passage through which the coil means may be moved from a first position external to said magnetic structure to a second position wherein said coil means may be rotated through a predetermined path to enter said two sides of said coil means in the air gaps, said magnetic structure including magnetic means which, when said coil means is in said second position, extends between said inner pole pieces by a path which is external to both the coil means and the predetermined path.

6. In an electrical instrument; a coil; a unitary magnetic structure including two inner pole pieces and two outer pole pieces, said pole pieces being arranged in pairs wherein each pair comprises an inner pole piece and an outer pole piece spaced to define an air gap for a separate one of two sides of said coil, and magnetically-independent means including a winding for directing magnetic flux through each of said air gaps; and means mounting said coil for rotation relative to said magnetic structure about an axis intermediate said two sides, said inner pole pieces being adjacent each other but spaced to define a passage through which the coil may be moved from a first position external to said magnetic structure to a second position wherein said coil may be rotated through a predetermined path to enter said sides of said coil in the air gaps, said magnetic structure including magnetic means which, when said coil is in said second position, extends between said inner pole pieces by a path which is external to both the coil and the predetermined path.

7. In an electrical instrument; coil means designed for rotation about an axis intermediate two sides thereof; a pair of magnetic structures, each having two magnetically-independent magnetic parts, each of said sides of the coil means being associated with a separate one of the magnetic parts of each of the magnetic structure, the magnetic parts associated with each of said sides defining paths for magnetic flux produced by current flowing in said coil means for producing solenoid forces acting between the parts and the coil means, pairs of said magnetic parts being reversely associated with the coil means to produce oppositely directed solenoid forces acting between the coil means and the magnetic parts to decrease the effects of said forces on movement of the coil means.

8. In an electrical instrument, a magnetic structure, coil means, and means mounting the coil means for rotation relative to the magnetic

11

structure about an axis, said axis being located intermediate two sides of said coil means, said sides being equidistant from any point on the axis, said magnetic structure comprising a pair of magnetic cores each having a separate part positioned between said axis and each of said sides of the coil means, a first one of said magnetic cores having a passage permitting movement of the coil means therethrough in a direction substantially parallel to said axis when said coil means is adjacent a first extreme of its path of rotation, and a second one of said magnetic cores having a passage permitting movement of the coil means therethrough in a direction substantially parallel to said axis when the coil means is adjacent a second extreme of its path of rotation, magnetic means cooperating with said magnetic cores for establishing a separate magnetic path having an air gap for each of said sides of the coil means, said magnetic paths being magnetically independent of each other, and separate means associated with each of said magnetic paths for establishing a magnetic field in each of said air gaps.

9. In an electrical instrument, a magnetic structure, coil means, and means mounting the coil means for rotation relative to the magnetic structure about an axis, said axis being located intermediate two sides of said coil means, said sides being equidistant from any point on the axis, said magnetic structure comprising a pair of magnetic cores each having a separate part positioned between said axis and each of said sides of the coil means, a first one of said magnetic cores having a passage permitting movement of the coil means therethrough in a direction substantially parallel to said axis when said coil means is adjacent a first extreme of its path of rotation, and a second one of said magnetic cores having a passage permitting movement of the coil means therethrough in a direction substantially parallel to said axis when the coil means is adjacent a second extreme of its path of rotation, said magnetic cores being spaced apart in the direction of said axis by a distance sufficient to permit movement of an end of the coil means therebetween, magnetic means cooperating with said magnetic cores for establishing a separate magnetic path having an air gap for each of said sides of the coil means, the magnetic path for each of the sides of the coil means including the two parts of the magnetic cores adjacent the associated side of the coil means, said magnetic paths being magnetically inde-

12

pendent of each other, and separate means associated with each of said magnetic paths for establishing a magnetic field in each of said air gaps, said magnetic paths being spaced from said passages and the space between the magnetic core to permit movement of the coil means through said passages and space.

10. A magnetic structure for an electrical instrument comprising a pair of spaced first and second inner magnetic pole pieces, a first outer magnetic pole piece spaced from the first inner magnetic pole piece to define therewith a first airgap, a second outer magnetic pole piece spaced from the second inner magnetic pole piece to define therewith a second airgap, said pole pieces having pole faces giving said airgaps arcuate configurations about a common axis, said airgaps being spaced angularly about the axis, a magnetic connector establishing the only magnetic path between the first pole pieces, a magnetic connector establishing a magnetic path independent of the first-named magnetic path between the second pole pieces, and a connector completing a connection between the inner pole pieces by a path external to the airgaps and the space between the inner pole pieces, said airgaps and the space defining a continuous Z-shaped passage.

11. A magnetic structure as claimed in claim 10 in combination with a second magnetic structure similar to the first-named magnetic structure, said structures being reversed relative to each other about a line transverse to the axis and being axially spaced from each other along the axis.

CECIL L. FREEDMAN.
